UNITED STATES PATENT OFFICE.

CLARENCE G. EUSTIS, OF CHICAGO, ILLINOIS.

KEY FOR BRAKE-SHOES.

SPECIFICATION forming part of Letters Patent No. 639,676, dated December 19, 1899.

Application filed May 6, 1899. Serial No. 715,841. (No model.)

To all whom it may concern:

Be it known that I, CLARENCE G. EUSTIS, a citizen of the United States, residing at Chicago, in the county of Cook and State of Illinois, have invented certain new and useful improvements in Keys for Brake-Shoes, of which the following is a specification.

The invention relates particularly to that class of keys which are used in connection with brake-shoes on railway-cars, and has particular relation to a key constructed in such manner as to automatically lock and hold itself in position, all of which will more fully hereinafter appear.

15 The object of the invention is to provide a brake-shoe with a simple, economical, and efficient key by which the head and shoe may be locked together in operative condition; and the invention consists in the features, combinations, and details of construction hereinafter described and claimed.

20 In the accompanying drawings, Figure 1 is a side elevation of a shoe and head held in operative engagement by means of my improved key, and Fig. 2 a perspective view of a key constructed in accordance with my improvements.

25 In the art to which this invention relates it is well known that the brake beam, head, and shoe are subjected to a large number of shocks coming quickly and successively, so that the ordinary wedge-shaped key is not altogether sufficient and does not meet all the requirements, in that it is occasionally jarred 30 out of position. My improvement, therefore, is intended primarily to remove this objection by providing a key which will automatically lock itself after it is driven into position and hold the parts in operative engagement 35 until extraneous force is applied to remove it from its engaging position, as will more fully hereinafter appear.

40 In using my improvements I use a brake-shoe head A of the desired size, shape, and 45 strength and which is provided with the usual lugs a and a' on the front face thereof

and at or near the center portion and with the lugs a² at or near the ends thereof, all of which serve to form a stay for the shoe B, the outer face of which, b, is of substantially 50 the curvature of the wheel.

To hold the shoe in operative engagement with the head, I provide the key C, which may be made of a forging or other material and of such width and thickness as to have a 55 certain amount of "spring" in it, and which is provided with a head c. This key is generally, when locked either from the side or front, substantially wedge-shaped and is driven in openings in the lugs a and a' of the 60 head and through an opening in the lug b' of the shoe, which usually serves to hold the parts in operative engagement. In order, however, to hold them more effectually in position and in a manner automatically lock 65 them in such position, the upper part of the key is provided with an offset or lug c', arranged on the front face thereof and adapted to bear against the inner surface of the shoe, thus acting to spring the upper part of the 70 key backwardly and the lower part of the key forwardly, so that the latch-shaped portion c² catches underneath the lug of the head and locks the parts together. To unlock the 75 key, the lower part of the key is pressed backwardly until its latch disengages with the lug, and the key may be removed by prying upwardly on the head or driving the lower part in the same direction with a hammer.

I claim—

80 A key for brake-shoes provided with an offset on the front face thereof adapted to contact the inner face of the brake-shoe and spring the lower part forwardly, and a latch part on the lower part of the key adapted to 85 engage with a lug on the head portion and lock the parts together, substantially as described.

CLARENCE G. EUSTIS.
